UNITED STATES PATENT OFFICE.

HERMAN C. MUELLER, OF MILWAUKEE, WISCONSIN, ASSIGNOR TO EVINRUDE MOTOR COMPANY, OF MILWAUKEE, WISCONSIN, A CORPORATION OF WISCONSIN.

IGNITER MAGNETO-GENERATOR.

1,147,038.

Specification of Letters Patent. Patented July 20, 1915.

Application filed June 27, 1914. Serial No. 847,582.

To all whom it may concern:

Be it known that I, HERMAN C. MUELLER, a citizen of the United States, residing at Milwaukee, county of Milwaukee, and State of Wisconsin, have invented new and useful Improvements in Igniter Magneto-Generators, of which the following is a specification.

My invention relates to improvements in igniter magneto generators for internal combustion engines of that type in which the fly wheel is provided with permanent field magnets and utilized as the rotor, the armature being relatively stationary and inclosed within the rim of the fly wheel.

In a former application filed July 17th, 1913, Serial No. 779423, I have shown and described one form of magneto generator of this type or class in which the axis of the armature crosses that of the crank shaft, the armature heads being diametrically opposite.

The object of my present invention is to further improve the armature stator in a magneto of the described class by providing an offset armature magnet detachably connected with head pieces which may be permanently secured to the supporting plate or disk at diametrically opposite points, whereby the armature coil or magnet may be removed, repaired, and replaced without disturbing the head pieces, and whereby in the construction of the magneto, the head pieces may be permanently secured to the supporting disk and their outer curved surfaces accurately machined without danger of displacement by subsequent readjustments.

A further object of my invention is to simplify and reduce the cost of construction of the armature and to more fully expose the timer mechanism and electrical connections, whereby repairs and readjustments are facilitated, the parts being constructed and organized with a view of providing a magneto generator which will operate reversibly in the sense that the rotation of the fly wheel may be reversed without affecting the efficiency of the magneto, and without requiring any readjustment, except a slight shifting of the timer lever to properly advance the spark for reverse movement.

In the drawings Figure 1 is an elevation of my improved magneto generator with a portion of the fly wheel broken away to expose the field magnets, pole pieces, and a portion of the armature. Fig. 2 is a sectional view, drawn on line $x-x$ of Fig. 1. Fig. 3 is an elevation of the stator, the fly wheel being removed. Fig. 4 is a detail end view of the armature, showing the same with the head piece separated from the central core, which carries the coil.

Like parts are identified by the same reference characters throughout the several views.

The crank shaft 1 is provided with a collar 2, having a cam projection 3 which operates the circuit breaker by actuating the arm 4 of the interrupter lever, whereby the arm 5 may be actuated once during each revolution of the crank shaft into contact with terminal 6. As soon as the cam 3 clears the interrupter lever 4, arm 5 will be retracted to circuit breaking position by the reaction of a spring 7 interposed between the arm 5 and the timer lever 8. For the purpose of this application, these parts may be regarded as of any ordinary construction.

The arm 4 is pivotally supported from a stator disk 10, and a stop pin 11 holds the extremity of said arm out of contact with the collar 2, but the rounded head 12 on the arm is in the path of cam projection 3. At one side of the crank shaft, preferably on the side opposite the timer lever, the centrally wound member 15 of the armature is mounted and detachably supported from the stator disk 10, as will now be explained. Armature head pieces 16 and 17 are secured to the supporting disk 10 at diametrically opposite points by screws or bolts 14. Each of these head pieces 16 and 17 is provided with an arm 18, which over-laps and is secured to one of the polar projections 19 of the core of the member 15 which carries the generating coils. Clamping bolts 20 are employed to bind the arms 18 rigidly to the core projections 19. It will therefore be observed that the central portion 15 of the armature, including the coil, is offset laterally

ally from the crank shaft and detachably connected with the armature head pieces 16 and 17. Therefore, if the armature coil burns out or is damaged in any manner, it 5 may quickly be removed by first removing the bolts 20 and then disengaging the coil and core by lateral movement.

The fly wheel comprises a disk 25 provided with a hub 26 and rim 27, and this fly wheel 10 is adapted to receive the armature within rim 27, as clearly shown in Fig. 2, the crank shaft being tapered and fitted to the hub 26 and secured thereto by a nut 28. A set of segmental permanent magnets 30 and 31 are 15 secured to the inner face of the fly wheel rim and are also connected by screws 32 with inwardly projecting segmental pole pieces 34 of the rotating field thus provided. The armature pieces or heads 16 and 17 are adapted to 20 span the gaps 35 between pole pieces 34 twice during each revolution of the fly wheel, and the eccentric 3 is so located with reference to the field pole pieces 34 that the interrupter lever will be actuated to close the circuit preparatory to the relative traverse of the gaps 35 by the armature heads 16 and 17, the circuit being broken immediately after the receding extremity of the field pole piece 25 draws away from the armature head. The 30 circuit is therefore broken substantially at the instant of maximum magnetic flux.

Owing to the fact that the circuit is closed immediately preparatory to the spanning of gap 35 between the armature heads 16 and 35 17, and broken at substantially the same interval following the central gap spanning position, it is obvious that the magneto can be operated regardless of the direction of fly wheel rotation. To reverse the engine, it is 40 therefore merely necessary to allow the rotation of the fly wheel to stop and then start it in the opposite direction with a slight shifting of the timer lever to properly advance the spark, as is common practice in the operation of magneto generators.

I do not deem it necessary to describe the electrical connections nor the details of construction of the various parts above mentioned, as the arrangement of the circuits 50 will be fully understood by any one skilled in this art. It may be stated, however, that the magnet core of the armature is preferably laminated and that the pole pieces are also laminated, as shown. Also that a condenser 38 is employed to secure a more effective discharge at the spark terminals.

My invention is peculiarly adapted for use 60 in connection with small quick running internal combustion engines used for operating motor boats, etc. The use of reversing gears in connection with such engines materially complicates the structure and increases the cost. By providing a reversible magneto, I am enabled to dispense with revers-

ing gearing, since I am able to almost instantly reverse the engine.

I claim—

1. A reversible magneto generator including an armature, comprising a centrally wound core and a set of segmental armature 70 head pieces detachably connected with the core and offset in one direction therefrom, whereby said armature may be assembled within a rotating field with the head pieces on diametrically opposite sides of the axis of 75 the field, and the centrally wound core offset laterally from said axis and head pieces.

2. An armature for igniter magneto generators, comprising a centrally wound core member and a set of segmental head pieces 80 connected with the core member and offset at one side thereof, said core member and its winding being wholly to one side of a line common to the centers of the head pieces.

3. The combination with the crank shaft 85 of an internal combustion engine, a rotary field magnet provided with segmental pole pieces and means for operating a circuit interrupter, of a relatively stationary support; an armature member provided with a current generating coil located at one side of the crank shaft, and a pair of segmental armature head pieces fixed to said support on opposite sides of the crank shaft and connected with said armature member upon 90 which the coil is located, the central portions of said head pieces being in a line which extends through the crank shaft, the coil being laterally offset from said line.

4. The combination with the crank shaft 100 of an internal combustion engine, a rotary field magnet provided with segmental pole pieces and means for operating a circuit interrupter, of a relatively stationary support, an armature member provided with a current generating coil located at one side of the crank shaft, and a pair of segmental armature head pieces fixed to said support on opposite sides of the crank shaft and connected with said armature member upon which the 110 coil is located, said armature member being detachably connected with the head pieces, substantially as set forth.

5. The combination with the crank shaft 115 of an internal combustion engine, a rotary field magnet provided with segmental pole pieces and means for operating a circuit interrupter, of a relatively stationary support, an armature member provided with a current generating coil located at one side of 120 the crank shaft, a pair of segmental armature head pieces fixed to said support on opposite sides of the crank shaft and connected with said armature member upon which the coil is located, said head pieces being adapted 125 to span the gaps between the field pole pieces successively during the rotation of the field, means for closing the armature circuit im-

mediately before its heads occupy the gap spanning position, and means for interrupting the armature circuit substantially at the instant of maximum magnetic flux as one of the field pieces is withdrawn from its respective armature head by the continued rotation of the field, substantially as set forth.

In testimony whereof I affix my signature in the presence of two witnesses.
